UNITED STATES PATENT OFFICE.

RENNIE E. HART, OF FLUSHING, MICHIGAN.

RECORDING ATTACHMENT FOR SCALES.

1,081,738.

Specification of Letters Patent. Patented Dec. 16, 1913.

Application filed July 30, 1912. Serial No. 712,307.

To all whom it may concern:

Be it known that I, RENNIE E. HART, a citizen of the United States, residing at Flushing, in the county of Genesee and 5 State of Michigan, have invented new and useful Improvements in Recording Attachments for Scales, of which the following is a specification.

My invention relates to printing devices 10 and more particularly to a recording apparatus for use in combination with scales of different types which attachment is in the form of printing devices automatically operated through the movement of certain apparatus worked in connection with the scale.

A primary object of my invention is to provide a printing attachment for platform scales which may be caused to record on an invoice, bill of lading or anything of like 20 nature the exact weight of the goods on the scale, the recording action being operated through the printing attachment before referred to which is automatically controlled by manually operating means after the scale 25 has been balanced.

Another object of my invention is to provide such an apparatus which shall be efficient in operation, simple in construction, and convenient in its location with relation 30 to the scale proper.

A still further object of my invention is to provide novel means for operating the recording apparatus, said operating means being controlled by the position of the 35 weights on the scale and arms which latter are automatically locked through the operation of said means.

Another object is to provide operating means for the recording apparatus which 40 shall be controlled by arms or equivalent devices yieldingly connected to the weights and positions of said arms determining of course the figures printed by the recording apparatus.

45 With the foregoing and other objects in view my invention consists in such details of construction and arrangement of parts as will be hereinafter more fully described and specifically pointed out in the appended 50 claims.

In describing my invention in detail reference will be had to the accompanying drawings wherein like characters denote like or corresponding parts throughout the 55 several views and in which;

Figure 1 is a view in front elevation of

my attachment and platform of the scale the coöperating mechanism being omitted. Fig. 2 is a vertical sectional view taken on the line 2—2 of Fig. 1. Fig. 3 is a similar 60 view taken on the line 3—3 of Fig. 1. Fig. 4 is a vertical section in detail taken on line 4—4 of said Fig. 1. Fig. 5 is a vertical section taken on the line 5—5 of Fig. 1 and looking in the direction opposite to that in which Figs. 2, 3 and 4 are illustrated. Fig. 6 is a detail view and elevation illustrating the printing wheels and coöperating mechanism. Fig. 7 is a top plan view of the same 65 wheels. Fig. 8 is an enlarged detail showing the means for turning the printing wheels. Fig. 9 is a detail view partly in section and partly in elevation more clearly illustrating the means for operating the vertical rods locking the weights and so forth. Fig. 10 is a perspective view of the detail. Fig. 11 is a perspective detailed view of the 70 operating lever and attaching mechanism. Fig. 12 is a detailed view in perspective of the bars forming a locking means for the 75 yieldingly mounted arms of the weights.

It will of course be understood that in reducing my invention to practice any suitable type or make of scale can be used. This forms no part of my invention and therefore has not been illustrated. The invention under construction is more in the nature of an attachment for types of scales already in use and well known in the art. It is essential of course that the scale to which it is to be applied be provided with the usual type of beam 1 and suspended in the usual manner from the arm 2 of the scale proper. If desired a suitable frame work for my device may be constructed such for instance as that provided by the horizontal member 3, vertical members 4 and 5 and so on. It will be again understood however that this is immaterial and forms no particular part of the invention in question. All that is 80 essential in this connection is that the framework adapted to contain the apparatus hereinafter to be described and to be disposed in the general position illustrated in Figs. 1 and 2 and 3 of the drawings be provided. It is also essential that this framework of whatever construction it may be, be formed with a suitable table or shelf 6 conveniently located, the advantages of which will be more clearly brought out 85

hereafter.

The scale beam illustrated and already 90

95

100

110

designated by the numeral 1 is provided with three weight arms 7—8 and 9 respectively. The first of these may be termed the "tens" arm, the second the "hundreds" arm 5 and the third the "thousands" arm, which of course are provided with the usual slideable weight 7', 8' and 9' respectively. My invention may be modified and adapted for use with scales having only one weight arm 10 or two such arms or more than three, should it be necessary, it having been illustrated in connection with the triple arm merely as an example and in order to clearly illustrate the operation of the device. On the rear sides 15 of the weights 7'—8' and 9' are formed brackets to which are pivotally connected arms 10—11 and 12 which are normally held in an upwardly inclined position by means of springs 13 of any suitable nature.

20 Running crosswise of the framework before spoken of and disposed below and to the rear of the arms 10—11 and 12, are slot bars 14—15 and 16 respectively, arranged in step formation, the lowest one being below the arm 10 the middle beneath the arm 11, and the upper one below the arm 12 and out of engagement with said arms when the latter are in their normal positions. As before mentioned the bars 14—15 and 16 are provided with slots designated by the numeral 17 which slots correspond in number and position with the units on the scale arm with which they coöperate. For instance there is a slot on the rod 14 opposite each pound 25 marked on the scale arm 7. The rod 15 is provided with a slot opposite each hundred marked on the arm 8 and the same is also true with regard to the rod 16, its slots are formed opposite each thousand marked on the arm 9. The fact will be appreciated that if it is desired to record units smaller than pounds the number of slots on the rod 14 will have to be increased. For instance if it is desired to record one-half pounds there 30 will have to be a slot opposite each one-half pound graduation on the scale arm 7. A correspondingly increased number of slots would have to be provided for one-quarter pound or smaller units if it should be desired 35 that such smaller units be recorded.

40 Disposed to the rear of each of the rods 14—15 and 16 and with their upper ends slightly below the upper edge of said rods are rows of vertical reciprocal plungers 45 18—19 and 20. The upper ends of these plungers members are each a little in the rear of the slots under the bars before referred to and there are as many such plunger members as there are slots. As before mentioned 50 these members are reciprocal vertically and may be supported in any desired way. They are yieldingly mounted and are normally held in their uppermost positions by means of suitable springs 21. Running lateral to 55 the framework above spoken of are shafts 22—23 and 24 suitably journaled. Said shafts are each provided with a series of projected pins 25 and each pin on each shaft is disposed a little beneath the lower most end of the corresponding plunger. When 60 therefore any other plunger on the rows 18—19 and 20 are depressed the result will be that the pin corresponding to the depressed plungers will be engaged and said pin will in turn rotate the shaft to which it is connected. The degree of rotation of the various shafts will be determined by the angle which the various pins make with their respective shafts as well as the length of the various plunger members which construction will have the result hereinafter 65 again referred to.

70 Attention has already been directed to the fact that the arms 10—11 and 12 are adapted to enter the various slots in the bars 14—15 and 16 respectively. From what has since been said it will be seen that when said arms enter such slots the ends of the arms will engage the plunger corresponding to the slot behind which it is disposed and the movement above mentioned will result. In 75 order that the various arms enter the slots suitable mechanism accomplishing this purpose may be employed. In the drawings have been illustrated a series of pivotally mounted bars 25—26 and 27 respectively disposed between the arms 10—11 and 12. These bars are normally held out of engagement with the arms by means of springs as 80 illustrated but it will be seen that upon their being moved on their pivots they will engage the arms and depress the same into the slots referred to as illustrated in Fig. 9. This operation may also be accomplished in any desired way one method being described 85 in the drawings in which I show a hand lever 28 pivoted to the side of the part of the framework and having connection with a vertically disposed pitman 29. The lower end of the member 29 may be connected by 90 means of a pin 30 passing through an opening in the member 4 of the framework with the lever 31 which is pivotally connected to the inner side of said framework and to which are attached cords 32 which are 95 guided to their respective pivoted bars 25—26 and 27. By this construction I am 100 enabled by simply depressing the hand lever 28 to lock the arms 10—11 and 12 on slots 105 opposite which they may be disposed and the rods 14—15 and 16 respectively and by the same movement to depress the corresponding plungers and operate the shafts 22—23 and 24 accordingly.

110 The printing or recording mechanism is 115 disposed beneath the table or shelf 6 above referred to the actual printing being done from a series of wheels 33—34—35 and 36 120 which are freely mounted on the shaft 37 suitably supported so as to cause said wheels 125 130

to register with an opening 6' in said table. The wheels 33 and 34 are connected together so as to make it impossible for them to rotate independently of each other. The 5 wheels 35 and 36 have no connection with 33 and 34 or with each other each being independently mounted. The first two referred to carry the tens and units, and correspond with the weight arm 7 and the scale beam. 10 The wheel 35 carries the hundreds and corresponds with the arm 8, and the wheel 36 carries the thousands and corresponds with the arm 9. Suitable means are provided for holding all of these wheels in their normal 15 positions. It would probably be found advisable to do this by three weights suspended from hubs of the wheels as is illustrated in detail from Fig. 6. Because of the large number of numerals carried by the 20 wheels 33 and 34 it would probably be necessary for these to rotate an entire revolution, whereas the others carrying a comparatively small number of numerals would probably not have to rotate at any time more than 25 about one-tenth of a revolution. The method of holding them in their normal positions is perfectly adapted to these conditions. As soon as the weight 38 is suspended from the hub between the wheels 33 and 34 it will be wound upon said hub as well as rotate. The weight 39 is suspended from the hub of the wheel 35 and the weight 40 from the hub of the wheel 36 and will operate in a similar manner. 30 Any suitable connection may be made between the wheels 33-34-35 and 36 and the shafts 22-23-24 whereby said wheels may be suitably revolved when said shafts are operated as in the manner above described 35 at length. One way in which this can be done is illustrated in Figs. 4-7- and 8 of the drawings. Here is shown the shafts referred to provided with hubs 41-42 and 43 around which are partly wound tapes 44-45 and 46 respectively. The other ends of these tapes are similarly wound around hubs connected to the several wheels as for instance around the hub 47. As a consequence of this construction the rotation or partial 40 rotation of any of the shafts 22-23 and 24 by means before set forth will cause a corresponding movement of the wheels 33-34 and 35 and 36. This will bring the desired numerals in rotation with the opening 6' in the table 6. Above this opening or adjacent thereto may be disposed a stamping mechanism 48 of the well known type, as this forms no part of my invention it has not 45 been illustrated in detail. 50 It is thought that the construction and operation of the invention in question will be apparent from the foregoing description. It will be seen that first of all the scale beam is balanced in the usual way. When the same is balanced the hand lever 28 is de-

pressed which through the operation before described rotates the shafts which in turn partially rotate the printing wheels bringing the numerals corresponding with the weight of the goods exactly beneath the opening 6'. 70 The bill of lading, invoice or any similar form may be placed over said opening and the stamping apparatus incidentally referred to above is operated to stamp the exact weight thereon. This obviates the necessity of writing on the weight in pencil and avoids the chance of error incident to such a procedure. It saves considerable time, trouble and inconvenience and absolutely assures accuracy. 75

I desire it to be understood that my invention as described above cannot be considered as perfected in its details, all I claim at the present time being the principles involved in its operation. Changes may be 80 made without departing from the spirit of my invention provided such changes fall within scope of the appended claims.

Having thus fully described my invention what I claim as new and desire to secure by 90 Letters Patent is:—

1. In a device of the character described, a scale beam, a weight device movable relatively to the beam having a projecting member mounted slidably in a plane longitudinally of said beam and movable in another plane, printing apparatus, and means for setting the type of said printing apparatus through movement of said projecting member in said other plane. 95

2. In a device of the character described, a downwardly movable scale beam, a weight freely movable on said beam, an arm on said weight, printing apparatus including movable type, and means whereby the type of 100 said printing apparatus may be set having a depressible member operable upon engagement of said arm therewith.

3. In a device of the character described, a scale beam, a weight freely movable thereon, an arm carried by said weight movable in a plane transversely of the beam, printing apparatus including movable type, and means for setting the said type of said printing apparatus through movement of 105 said arm. 110

4. In a device of the character described, a scale beam, a weight freely adjustable with respect thereto, an arm yieldingly connected to said weight, printing apparatus including movable type, means for moving said arm, and means whereby the movement of said arm sets the type of said printing apparatus. 115

5. In a device of the character described, a scale beam, a weight thereon, an arm yieldingly connected to said weight, a plurality of plungers each of which is adapted to be engaged to said arm, means for operating said arm, printing apparatus in- 120 125 130

cluding movable type, and means whereby the operation of said arm and a plunger sets the said type of said apparatus.

6. A device of the character described comprising a scale beam, a weight adjustable thereon, a plurality of vertically reciprocable plungers, means, the position of which is controlled by said weight, for operating any of said plungers, printing apparatus including movable type and means whereby the type of said printing apparatus may be operated through the movement of said plunger.

7. In a device of the character described, a scale beam, a weight adjustable thereon, a plunger, means for operating said plunger carried by said weight, means for preventing the lateral movement of the plunger operating means when the same is in operation, printing apparatus including movable type, and means for setting the type of said printing apparatus through the movement of said plunger.

8. In a device of the character described, a scale beam, a weight adjustable thereon, a yieldingly mounted arm on said weight, a plurality of reciprocable plungers, means for forcing said yieldingly mounted arm into engagement with the upper ends of any of said plungers, means for locking said arm against lateral movement while the same is engaging said plungers, printing apparatus including movable type, and means whereby the movement of said plungers sets the said type of said apparatus.

9. In a device of the character described, a scale beam having a plurality of weight arms, a weight in each of said arms, yieldingly mounted arms connected to said weights and extending therefrom, a plurality of reciprocable plungers arranged in rows corresponding in number and position to said yieldingly mounted arms and adapted to be engaged by said arms, means for operating said arms, whereby the same are brought into engagement with corresponding plungers, printing apparatus including movable type, and means whereby the op-

eration of said plungers sets the type of 50 said printing apparatus.

10. In a device of the character described, a scale beam, a weight adjustable thereon, a yieldingly mounted arm connected to said weight, a pivotally mounted bar above said arm and adapted to engage and depress the same when turned, means for turning said bar, printing apparatus including movable type, and means whereby the turning of said bar and the depression of said arm 60 sets the said type of said printing apparatus.

11. In a device of the character described, a scale beam, a weight adjustable on said beam, an arm pivotally connected to said weight and extending therefrom, means for moving said arm, a plurality of plungers any one of which is adapted to be engaged by said arm when the latter is depressed, a plunger selected being controlled by the position of the weight on the scale beam, printing apparatus including movable type, and means for setting the said type of said printing apparatus through the operation of said plunger.

12. In a device of the character described, a scale beam having a plurality of weight arms, a weight slidable on each arm, yieldingly mounted arm connected to each weight, a plurality of plungers mounted in 80 rows corresponding in position to the yieldingly mounted arms, and in number to the weight arms, the plungers in each row corresponding in number and position to the units on the weight arm with which they respectively coöperate, means for moving the yieldingly mounted arms whereby they may be brought into engagement with said plungers to operate the same, the plungers selected being determined by the positions 90 of the weights, printing apparatus, and means whereby the operation of said plungers control said printing apparatus.
